ATTY.

UNITED STATES PATENT OFFICE.

ROBERT BRUCE FORSYTH, OF CHRISTCHURCH, NEW ZEALAND.

MILKING-MACHINE PULSATOR.

1,420,421.

Specification of Letters Patent. Patented June 20, 1922.

Application filed January 4, 1922. Serial No. 526,972.

To all whom it may concern:

Be it known that I, ROBERT BRUCE FORSYTH, a subject of the King of Great Britain, residing at Christchurch, New Zealand, 5 have invented new and useful Improvements in and Relating to Milking-Machine Pulsators, of which the following is a specification.

This invention relates to pulsators for 10 milking machines and refers to the particular form of pulsator which is adapted to operate in response to a primary pulsation and when so operated to produce a secondary pulsation.

15 In a pulsation of this nature it is however impossible to provide efficient lubrication for the moving parts, the result being, in the case of the constructions hitherto employed, that the efficiency of the device has 20 gradually declined in consequence of wear of such parts.

It is the object of the present invention therefore to provide a simple and novel construction whereby the full effect of the primary pulsation will be secured and the above 25 mentioned trouble, due to wear of the working parts, avoided.

In carrying this object into effect the present invention comprises a cylinder or valve- 30 housing within which is adapted to reciprocate a piston or operable valve-member. The said cylinder is formed around its interior with peripheral shoulders arranged in pairs of which the individual shoulders are 35 in opposed relation to each other.

Around the periphery of the piston also are formed peripheral shoulders likewise arranged in pairs to correspond with those of the cylinder and with which they are 40 adapted to come into and out of abutment as the piston reciprocates.

Arranged to enter the cylinder at points between the two shoulders of the latter constituting the pair or each pair are ports connecting with the pulsation chambers of the 45 teat-cups or other portions of the plant to which the secondary pulsation is to be communicated.

Arranged to enter the cylinder at points 50 to either side of the said pair or each pair of shoulders are ports or means of communication with the atmosphere and with an

appropriate source of vacuum respectively such atmospheric and vacuum ports being arranged to occur in alternate sequence in 55 a direction lengthwise with the cylinder.

The term "vacuum" used in this specification includes any partial vacuum such as usually employed in milking machines.

The arrangement is such as the piston re- 60 ciprocates the action of the shoulders of the latter in coming into and out of abutment with those of the cylinder will place the said pulsation ports in communication with the said atmospheric and vacuum ports al- 65 ternately thereby producing the secondary pulsation.

The device may be arranged either to produce a single cycle of pulsations or to produce a differential or double cycle of pulsations that is to say one in which two pulsation ports or sets of ports are employed and in which one of such pulsation ports or sets of ports is in communication with atmosphere at the moment the other pulsation port 70 or set of ports is in communication with vacuum, a method sometimes employed in claw pulsators in order that the teat-cups 75 may be pulsated in pairs.

For the purpose of producing the said 80 reciprocal movement of the piston, there is provided a chamber having a portion connectable to vacuum, a second portion under atmospheric or approximately atmospheric pressure, and a third portion connectable to 85 the primary pulsation.

Arranged within the said chamber and operatively connected with the said piston are a pair of diaphragms, one of which constitutes a yieldable partition between the 90 said vacuum and atmospheric portions while the other diaphragm, which is of relatively greater effective area, constitutes a yieldable partition between one of the said portions and the primary pulsation portion. 95

The arrangement is such that the difference of pressure at the two sides of the smaller diaphragm tends to cause the latter to operate the piston constantly in one direction. At one period of the primary pulsation the other or larger diaphragm is also subject to difference in pressure tending to cause it to operate the piston in the opposite direction to that of the aforemen- 100

tioned tendency of the other or smaller dia-
phragm. The relative areas of the two dia-
phragms are such that under the above men-
tioned conditions the larger diaphragm will
5 prevail and operate the piston against the
tendency of the smaller diaphragm. During
the other period of the primary pulsation
however the pressures at the two sides of
the larger diaphragm will be equal or ap-
10 proximately so thus rendering such dia-
phragm incapable of effectively opposing the
smaller diaphragm which will in conse-
quence operate the piston in the other or
reverse direction. In this manner the com-
15 bined operation of the two diaphragms will
produce reciprocal movement of the piston
in step with the primary pulsation.

In order that the nature of the invention
and its construction may be clearly under-
20 stood, it will now be particularly described
with reference to the accompanying drawings
in which:—

Fig. 1 is a plan view of a claw-pulsator
constructed in accordance with the present
25 invention, and adapted to provide a differen-
tial or double cycle of pulsations.

Fig. 2 is a sectional elevation of the same
along the line A—B Fig. 1, the piston being
30 shown in its mid-stroke position, and,

Fig. 3 is a view of the central portion of
35 the cylinder turned axially round to a position
at right angles with that shown in
Fig. 2, the front portion being shown broken
away in order to illustrate the positions of
the pulsation ports.

1 is a chamber having four nipples 2, 3, 4
and 5 to receive the connections of the milk-
chambers of the four teat-cups of the set,
40 such chamber 1 being adapted to provide
the necessary communication between the
said connections and the milk-pipe 6 in a
similar manner to that of certain construc-
tions previously employed.

According to the present invention upon
45 the necessary cover 8 of the chamber 1 is
carried a vertically disposed cylinder or
housing 9 which is so bored as to provide
four shoulders, viz, 10, 11, 12 and 13, which
shoulders are arranged in opposed pairs as
50 shown.

Communicating with the bore of the cylinder
between the pair of shoulders 10 and
55 11 are two ports 14 and 15 constituting
the entrance to nipples 16 and 17 respec-
tively and by means of which nipples sec-
ondary pulsations are communicated to the
usual flexible connections of the pulsation
chambers of two of the teat cups of the set.

Similarly, communicating with the bore
60 of the cylinder between the pair of shoul-
ders 12 and 13 are two ports 18 and 19 con-
stituting the entrances of two nipples 20
and 21 respectively and by means of which
nipples secondary pulsations are communi-
65 cated to the usual flexible connections of

the pulsation chambers of the two remain-
ing teat cups of the set.

At points above the shoulder 10 and below
the shoulder 13 are provided ports 22 com-
municating between the bore of the cylin-
70 der and the atmosphere, while at a point
between the shoulders 11 and 12 is provided
a port 23 communicating between the bore
of the cylinder and a source of vacuum.

As here shown this vacuum connection is
75 provided by means of a nipple 24 communi-
cating with the port 23 and so connected
by means of a flexible connection 25 with
a nipple 26 communicating with the cham-
ber 1.

Adapted to reciprocate within the cylin-
der 9 is a piston 27, which fits loosely or with
a certain amount of clearance within the
portion of such cylinder extending between
the various ports above mentioned and
85 which piston is provided with two per-
ipheral flanges one of which 28 lies between
the shoulders 10 and 11 while the other
flange 29 lies between the shoulders 12
and 13.

The upper and lower surfaces of the
flange 28 constitute an opposed pair of
shoulders adapted to come into and out of
abutment with the shoulders 10 and 11 re-
spectively and similarly the upper and lower
95 surfaces of the flange 29 constitute an op-
posed pair of shoulders adapted to come into
and out of abutment with the shoulders 12
and 13 respectively.

The arrangement is such that when the
100 piston is at the upper end of its stroke the
upper shoulder of the flange 28 will be in
abutment with the shoulder 10 while the
lower shoulder of the said flange 28 will be
clear of the shoulder 11, the pulsation ports
105 14 and 15 will therefore be cut off from com-
munication with the upper air ports 22 and
placed in communication with the vacuum
port 23. In this position of the piston also
the upper shoulder of the flange 29 will be
110 in abutment with the shoulder 12 while the
lower shoulder of such flange 29 will be
clear of the shoulder 13 thereby intercepting
communication between the vacuum port 23
and the pulsation ports 18 and 19 and plac-
ing such pulsation ports in communication
115 with the lower air ports 22.

Upon the piston moving to the lower end
of its stroke the lower shoulder of the flange
28 will come into abutment with the shoul-
120 der 11 while the upper shoulder of such
flange will be clear of the shoulder 10 thereby
intercepting communication between the
vacuum port 23 and the pulsation ports 14
and 15 and placing such pulsation ports
125 in communication with the upper air ports
22. Simultaneously therewith the lower
shoulder of the flange 29 will come into
abutment with the shoulder 13, while the
upper shoulder of such flange 29 will be
130

clear of the shoulder 12, thereby intercepting communication between the lower air ports 22 and the pulsation ports 18 and 19 and placing pulsation ports in communication with the vacuum port 23.

In this manner therefore the reciprocation of the piston will produce a differential or double cycle of pulsations.

If so desired the positions of the atmospheric and vacuum ports may be reversed, that is to say an atmospheric port may be substituted in place of the port 23 in which case two vacuum ports will be provided in place of the ports 22.

For the purpose of so actuating the piston, the lower end of the latter is arranged to project downward into the chamber 1 in the upper portion of which are provided two diaphragms 30 and 31.

The central portions of the said diaphragms are attached to the piston while their outer peripheries are attached to the walls of the chamber 1 in any suitable manner as by the provision of suitable seats or shoulders upon which the said peripheries are retained by the action of the vacuum. The chamber 1 is thus partitioned into three portions, viz. a lower portion beneath the diaphragm 31 and which portion is under continuous vacuum, an intermediate portion between the two diaphragms maintained under atmospheric pressure or approximately so as by means of openings or vents 32 communicating between such portion of the chamber 35 and the atmosphere, and an upper portion above the diaphragm 30 to which portion is communicated the primary pulsation, as by means of the nipple 33.

The arrangement is such that the diaphragm 31 constituting a partition between the continuous vacuum of the lower portion of the chamber 1 and the atmospheric pressure of the intermediate portion, will tend continually to draw the piston downward to the lower end of its stroke. During the atmospheric or high pressure period of the primary pulsation the pressures above and below the diaphragm 30 will be equal or approximately so and consequently such diaphragm will be incapable of effectively opposing the said tendency of the lower diaphragm 31 which latter will therefore cause the piston to perform its downstroke.

During the vacuum or low pressure period of the primary pulsation however the diaphragm 30 being under vacuum at its upper side and atmospheric pressure at its lower, will exert an upward pressure upon the piston and so cause the latter to perform its upward stroke against the tendency of the diaphragm 31.

In order that it may perform this action the diaphragm 30 is made of the required relatively greater effective area than the diaphragm 31.

In construction the diaphragms 30 and 31 may be composed of thin sheet metal or other flexible material.

In the preferred form of the construction however, as here shown, such diaphragms 70 each consist of a central rigid plate or disc provided around its periphery with an annular portion of rubber or other like flexible material adapted to make an air-tight joint with such disc and with the wall of the containing chamber.

By this construction the yielding or flexible nature of the rubber will not only permit the required movements of the discs in response to the primary pulsation but will 80 also allow such discs sufficient freedom in a radial direction to find their correct positions and thus avoid any tendency on the part of such discs to throw the piston out of alignment with the cylinder.

In the preferred form of the construction also as here shown the said annular rubbers are united by a web 34 formed integral with such rubbers while the rigid discs are also united by a boss 35 and by means of which 90 boss the diaphragms are attached to the piston.

As a modification of the arrangement of the chamber 1 the positions of the atmospheric and vacuum portions of such chamber 95 may be reversed, that is to say the portion beneath the diaphragm 31 will be under atmospheric or approximately atmospheric pressure in which case the portion between the two diaphragms 30 and 31 will be in 100 communication with vacuum. In this arrangement of the construction, the diaphragm 31 will tend to carry the piston upward. During the vacuum period of the primary pulsation conditions above and below the diaphragm 30 will be equal or approximately so and consequently such diaphragm will offer no effective opposition to the upward movement of the piston under the said tendency of the diaphragm 31. During the atmospheric or pressure period of the primary pulsation however, the diaphragm 30 being under vacuum at its lower side and atmospheric pressure at its upper side will exert a downward pressure upon 115 the piston and so carry the latter to the lower end of its stroke against the aforesaid upward tendency of the diaphragm 31.

In the case of a claw pulsator or other pulsator in which the diaphragms are contained in a portion of a chamber connected with the milk-pipe, it would be necessary in the case of the last-described construction to provide a wall or partition to separate the atmospheric portion of such chamber immediately beneath the diaphragm 31 from the lower or remaining portion which is necessarily under vacuum. For this reason the first described form of the invention is considered preferable although an equally effec- 130

tive reciprocation of the piston can be obtained with either form.

The cover 8 is made removable from the chamber 1 in order to provide access to the interior of the latter for cleaning and other purposes. To permit of the piston 27 being placed within the cylinder also the latter is divided horizontally into three portions viz, a central portion containing the shoulders 11 and 12, an upper portion containing the shoulder 10, and a lower portion containing the shoulder 13.

For the purpose of clamping or securing the said parts together a screw 36 is provided and arranged to extend upward through the chamber 1 and through an axial bore in the piston to the top portion of the cylinder where it is received within a suitably tapped hole 37.

The foregoing description is given in order to clearly explain the construction and operation of the invention which is however applicable not only to a claw pulsator but also to any pulsator employed for the purpose of producing a secondary pulsation or pulsations in any portion of a milking machine plant.

Thus for example the construction may be applied to a milk-bucket where such is employed in which case the construction may be similar to that already described except for the fact that the upper portion of such bucket may take the place of the chamber 1.

Again the device may be employed as a relay or intermediate pulsator adapted to be inserted in any desired portion of the pulsation line, in which case in lieu of the chamber 1, a special chamber or housing will be provided to contain the diaphragms 30 and 31.

A similar construction will be employed also in cases where the pulsator is used to operate a milk-releaser.

In cases where the pulsator is designed to supply a single cycle of secondary pulsations, as in the case of a relay or releaser pulsator, the cylinder will be provided with a single pair of opposed shoulders and with which are adapted to co-act a single pair of opposed shoulders formed upon the piston.

I claim:

1. The combination with a milking machine including a source of vacuum, a source of primary pulsation, and apparatus adapted to receive secondary pulsations, of a secondary pulsator operable in response to said primary pulsation and adapted to produce said secondary pulsations comprising a chamber having a portion connected with vacuum, a second portion under approximately atmospheric pressure, and a third portion connected with the primary pulsation, a diaphragm in said chamber constituting a yieldable partition between said vacuum and atmospheric portions, a second diaphragm

therein of relatively greater effective area constituting a yieldable partition between one of said portions and said primary pulsation portion, and valve-means positively connected with both of said diaphragms so as to be mechanically operated thereby and adapted when so operated to place aforesaid secondary pulsation receiving apparatus in communication with vacuum and atmosphere alternately. 70

2. The combination with a milking machine including a source of vacuum, a source of primary pulsation, and apparatus adapted to receive secondary pulsations, of a pulsator operable in response to said primary 80 pulsation and adapted to produce said secondary pulsations, comprising a chamber, a pair of diaphragms therein adapted to reciprocal movement under the combined influences of vacuum, of approximately atmospheric pressure, and of the primary pulsation, a valve-housing mounted upon said chamber, an operable valve-member therein positively connected with both of said diaphragms so as to be reciprocated thereby, 85

ports connecting with vacuum and with atmosphere spaced longitudinally in said housing, means of communication with aforesaid secondary pulsation receiving apparatus located between said vacuum and atmospheric ports, opposed peripheral shoulders around the interior of said housing and located between said means of communication and said vacuum and atmospheric ports, and corresponding opposed peripheral shoulders formed upon said operable valve-member adapted when the latter is reciprocated to come into and out of abutment with said shoulders of the housing thereby connecting said means of communication with vacuum 95 and atmosphere alternately. 100

3. The combination with a milking machine including a source of vacuum, a source of primary pulsation, and a plurality of two-chamber teat-cups, 110 of a pulsator operable in response to said primary pulsation and adapted to produce a differential secondary pulsation in the pulsation chambers of said teat-cups and comprising a chamber, a pair of diaphragms therein adapted to reciprocal movement under the combined influence of vacuum, of approximately atmospheric pressure, and of the primary pulsation, a valve-housing mounted upon said chamber, an operable valve-member in said housing positively connected with both of said diaphragms so as to be reciprocated thereby, 115 ports communicating with the atmosphere and with vacuum spaced in alternate sequence longitudinally in said housing, a plurality of secondary pulsation ports located between said atmospheric and vacuum ports certain of such pulsation ports being connected to the pulsation chambers of certain of said teat- 120 125 130

5 cups and the remainder of such pulsation ports being connected to the pulsation chambers of the remainder of said teat-cups, opposed pairs of peripheral shoulders around
 10 the interior of said housing separating said pulsation ports from the adjacent vacuum and atmospheric ports in each case, and corresponding opposed pairs of peripheral shoulders formed upon said operable valve
 15 member, one shoulder of each pair upon said member being adapted to abut with one shoulder of each pair upon said housing when said member is in one extreme position thereby placing certain of said pulsation ports in communication with vacuum and the remainder of such pulsation ports in communication with atmosphere while the remaining shoulders of said member are adapted to similarly abut with the remaining
 20 shoulders of the housing when said member is in its other extreme position thereby reversing such connections of the pulsation ports.

4. The combination with a milking machine including a source of vacuum, a source 25 of primary pulsation, and apparatus adapted to receive secondary pulsations, of a secondary pulsator operable in response to said primary pulsation and adapted to produce
 30 said secondary pulsations comprising a chamber having a portion connected with vacuum a second portion under approximately atmospheric pressure, and a third portion connected with the primary pulsation, a diaphragm constituting a yieldable partition between said vacuum and atmospheric portions, a second diaphragm of relatively greater effective area constituting a
 35 yieldable partition between one of said portions and said primary pulsation portion, each of said diaphragms consisting of a flex-

ible annular portion connecting with the wall of said chamber and a central rigid portion connected with said annular portion, and valve-means positively connected 45 with said rigid portions of both of said diaphragms so as to be mechanically actuated thereby and adapted when so operated to place aforesaid secondary pulsation receiving apparatus in communication with vacuum and atmosphere alternately.

5. The combination with a milking machine including a source of vacuum, a source of primary pulsation and apparatus adapted to receive secondary pulsations, of a secondary pulsator operable in response to said primary pulsation and adapted to produce 55 said secondary pulsations comprising a chamber, a pair of diaphragms therein adapted to reciprocal movement under the combined influence of vacuum, of approximately atmospheric pressure, and of the primary pulsation, a cover for said chamber, a valve housing upon said cover and having connections to atmosphere, to vacuum, and 60 to said secondary pulsation, receiving apparatus, a valve member within said housing reciprocal by said diaphragms and adapted to co-act with said housing to place said secondary pulsation receiving apparatus in 65 communication with atmosphere and vacuum alternately, and a screw extending through said chamber and through an axial bore in said operable valve-member and whereby said chamber, its cover and valve- 70 housing are secured together.

In testimony whereof I have signed my name to this specification.

ROBERT BRUCE FORSYTH.
